ROOFING SUPPORT

John Blandy Llewellyn, Fair Oak, England, assignor of one-half to Mellowes and Company Limited, Sheffield, county of York, England

Application October 17, 1942, Serial No. 462,381
In Great Britain October 23, 1941

11 Claims. (Cl. 108—33)

This invention relates to roofing supports, more particularly those designed for the support of tiles or slates. Heretofore wooden battens or laths have generally been nailed to the rafters to support the roofing material but the nails are subject to rust and corrosion especially when the timber is not adequately seasoned, with the result that the battens or laths are apt to slip down inclined rafters causing tiles or slates to be dislodged.

It is the primary object of the present invention to provide an improved roofing support by the employment of which the disadvantages indicated above are reduced in effect if not wholly avoided.

A further object is to provide a metal roofing support from strip metal of sufficient strength to bear the weight of roofing material, capable of automatically obtaining a grip on inclined rafters when thus subjected to the load of roofing material and also automatically providing means for ventilating the surfaces of the rafters and of the roofing supports themselves thereby keeping these surfaces dry and reducing liability to rust or corrosion.

Other objects will become apparent from a perusal of this specification.

A roofing support according to the present invention comprises a longitudinally flanged metal strip of which at least one side edge is adapted, as by being sharpened, serrated or crimped, to obtain a grip on inclined rafters under the load of roofing material on the support.

The metal strip is preferably of channel formation, having a central or base portion between two side flanges.

One or both of the flanges may be at an obtuse angle with the central or base portion of the strip thereby conduced to the ease with which the supports obtain a grip on inclined rafters, enabling the supports to be nested one within another and facilitating packing for transport or storage whilst this nesting property also facilitates the production of overlapping joints between aligned supports and possesses other advantages.

The flange with a grip obtaining edge is preferably at an obtuse angle with the central or base portion of the strip and when the other flange is at right angles to the central portion it may be narrower than the obtuse angled flange.

The metal strip may be perforated at uniform intervals and these perforations are preferably substantially circular but slightly elongated in

the direction of the strip length in order to allow of expansion and contraction of the strip when secured by nails engaging the perforations.

The metal strip may be stiffened by a series of rib-like projections pressed across the junction of the strip with its flange. A scale of length may be marked on the strip.

In use a series of the roofing supports extends across inclined wooden rafters with a grip obtaining flange of each strip in contact with the rafters at a lower level than any other point of contact of that strip with the rafters. The roofing material is supported by and engaged with such roofing supports in any desired manner.

Nails, screws or like fixing devices may pass through the perforations of the roofing supports into the rafters.

When the metal possesses nesting properties each roofing support may comprise nested strips in order to increase the strength and stiffness of the supports.

In the accompanying drawing—

Figure 1 is a sectional isometric view of a roofing support according to the present invention:

Figures 2, 3 and 4 are views similar to Figure 1 illustrating modifications:

Figure 5 is an elevation of roofing material supported according to the present invention:

Figure 6 is a sectional side view of Figure 5:

Figure 7 is an enlarged sectional view taken on the line 7—7 of Figure 5:

Figure 8 is an enlarged fragmentary plan of the central portion of the roofing support:

Figure 9 is an isometric view of nested roofing supports.

Like reference numerals indicate like parts throughout the drawing.

40 The roofing support illustrated in Figure 1 comprises a metal strip of channel formation having a central or base portion 10 between two longitudinal side flanges 11 and 12 respectively. The flange 11 is at an obtuse angle, conveniently about 105°, with the central portion 10 and the flange 12 is at right angles to the central portion. The free edges of both flanges 11 and 12 are shown sharpened at 13 by a bevelled

45 formation of their edge regions although, if desired, the sharpened edge 13 may be applied only to the obtuse angled flange 11.

46 The central portion 10 of the metal strip is perforated along the centre line with holes 14 at uniform intervals which are less than the width of the rafters 15 on which the strip is to

be laid, so that at least one hole 14 shall be available for nailing the strip to each of the rafters whatever distance the rafters may be spaced apart. As shown in Figure 8, the perforations 14 are slightly elongated from a circular form in the direction of the strip length.

The roofing strip is shown in the position of use on an inclined rafter 15 with its obtuse angled flange 11 making contact with the rafter 15 at a lower level than the right angled flange 12. It will be appreciated that the weight of roofing material supported by the metal strip tends to cause the sharpened edge 13 of the lower obtuse angled flange 11 and also, though to a less extent perhaps, the sharpened edge 13 of the upper flange 12, to bite into and thus to obtain a grip on the inclined rafter 15. In order that when in use the central portion 10 of the strip may be substantially parallel with the upper surface of the rafter 15 the right angled flange 12 is somewhat narrower than the obtuse angled flange 11.

The roofing support illustrated in Figure 2 is similar to the one shown in Figure 1 but the grip obtaining edges of the flanges 11 and 12 are serrated, being formed with saw teeth 16 instead of being otherwise sharpened.

In the modification shown in Figure 3 the edge regions of the flanges 11 and 12 are crimped as shown at 17 to produce the desired tendency to grip the inclined rafter 15.

It will be appreciated that where the crimping 17 forms an exterior convex flute in the flange the exterior corner of the flange edge will be presented to the rafter 15 and where the crimping produces an interior convex flute the inner corner of the flange edge will be presented to the rafter with the result that each flange will have a number of separated gripping portions.

In the modification illustrated in Figure 4 the strip providing the roofing support is stiffened and reinforced by the formation of a series of rib-like projections 18 pressed across the junction of the central portion 10 of the strip with its flanges 11 and 12. As shown in Figure 4 the stiffening portions 18 project inwardly but, if desired, they may be pressed from the other side of the strip so as to project outwardly.

In use a series of the metal strips 10, 11, 12 comprised in the roofing supports extends across the inclined wooden rafters 15 as illustrated in Figures 5 and 6 preferably, as shown, with the obtuse angled grip obtaining flange 11 of each strip at a lower level than any other point of contact of that strip with the rafters.

Each strip is preferably secured in place by means of nails indicated at 19 in Figures 6 and 7 driven into the rafters through those perforations 14 which coincide with the rafters.

It will be appreciated that the elongation of the perforations 14 will ensure clearances between these perforations and the nails 19 and thus enable the metal strips to expand and contract under varying thermal conditions without causing distortion of the metal strips.

Tiles 20 and 21 are illustrated as the roofing material which is supported on the metal strips 10, 11, 12. The tiles 20 comprised in the two upper courses illustrated are provided with downwardly projecting lugs or nibs 22 which engage the upper right angled flanges 12 of their supporting strips. Those tiles 20 which overlap a rafter 15 may be additionally secured by some of the nails 19 passing through perforations of the tiles made to register with the strip perfora-

tions 14, as indicated by dotted lines at 19 in Figure 7.

Tiles intermediate of the rafters 15 may be anchored to the strips by means of nails 23 passing through registering perforations of tiles and strips and bent into engagement with the inner surface of the central portions 10 of the strips as indicated at 24 in Figure 7 although the nails 23 may be bent round the flange edges of the strips if desired.

Slates or the nib-less tiles 21 illustrated in the lower courses of Figures 6 and 7 are shown secured by the nails 19 where the tiles overlap the rafters and by the nails 23 with their bent portions 24 where the tiles are situated between rafters.

If desired, however, the tiles or slates 21 which overlap the rafters 15 may be secured by nails passing through tile or slate perforations into the rafters 15 and bearing against the upper flanges 12 of the roofing supports. In this case the intermediate tiles or slates may be secured by the nails 23 bent round the edges of the flanges 12 of the roofing supports or these tiles or slates may be perforated at different distances from their upper edges in order that these edges may be in alignment when the perforations are engaged by the nails 23.

If desired both the flanges 11 and 12 may be at an obtuse angle with the central portion 10 of the metal strip and it will be understood that the obtuse angled arrangement of one or both flanges will enable the strips to be nested one within the other as shown in Figure 9 thus facilitating packing for transport or storage. This nesting property also enables the end of one strip to overlap the end of another strip where the length of roof exceeds the length of a single strip. Moreover, two or more nested strips, as illustrated in Figure 9 may be fixed across the rafters 15 to provide a roofing support of greater strength and stiffness than a single strip.

Figure 9 also indicates at 25 a scale marked on the central portion 10 of the strip for convenience in roofing a building.

In some cases the intermediate tiles or slates may be secured to the metal roofing supports of the invention by means of cement which may be keyed to the supports through their perforations 14.

The metal roofing supports, as well as the nails or other metal fixing devices, are preferably protected from rust and corrosion by being galvanized or otherwise covered with a protective metal coating but it will be appreciated that even if rusting or corrosion takes place the automatic grips obtained by the metal strip on the rafters will counteract any tendency for the strips to slip down inclined rafters and to dislodge the tiles or slates. Moreover the construction of the roofing supports and their combination with the rafters automatically provide means for ventilating the surfaces of the rafters and of the roofing supports thereby keeping these surfaces dry and reducing liability to rust or corrosion.

It is always preferred to have the upper flange 12 at right angles both to the central portion 10 of the roofing support and to the rafters 15 since such a right-angled arrangement not only stiffens the strip but also counteracts any tendency for the strip as a whole to collapse under the load of the roofing material and wind pressure thereon. Partial collapse of the obtuse angled flange 11 would increase the grip of the roofing support on

the rafter without imparting any movement to the tiles or slates bearing on the roofing support.

What I claim is:

1. A roofing support comprising an elongated metal strip of inverted channel formation having a central portion between two side flanges of which at least one side flange is at an obtuse angle with the central portion of the strip and has an edge formed with grip obtaining means for embedment in inclined wooden rafters under the load of roofing material on the support.

2. A roofing support comprising an elongated metal strip of inverted channel formation having a central portion between two side flanges of which at least one side flange is at an obtuse angle with the central portion of the strip and has an edge formed with grip obtaining means for embedment in inclined wooden rafters under the load of roofing material on the support and the other side flange is at right angles to the central portion and is narrower than the obtuse angled flange.

3. A roofing support comprising a metal strip of channel formation having a central portion, perforated at uniform intervals with holes which are substantially circular but slightly elongated in the direction of the strip length, between two side flanges of which at least one side flange has an edge formed to obtain a grip on inclined wooden rafters under the load of roofing material on the support.

4. A roofing support comprising a metal strip of channel formation having a central portion between two side flanges and stiffened by a series of rib-like projections pressed across the junction of the central portion with the side flanges and at least one side flange has an edge formed to obtain a grip on inclined wooden rafters under the load of roofing material on the support.

5. The combination with a roof having inclined wooden rafters of a series of roofing supports extending across the rafters and each comprising a longitudinally flanged metal strip of which at least one flange has a grip-obtaining edge in contact with the rafters at a lower level than any other point of contact of that strip with the rafters and roofing material supported by and engaged with such roofing supports.

6. The combination with a roof having inclined wooden rafters of a series of roofing supports extending across the rafters and each comprising a longitudinally flanged metal strip of which at least one flange has a grip-obtaining edge being in contact with the rafters at a lower level than any other point of contact of that strip with the rafters, fixing devices passing through perforations of the roofing supports into the rafters and roofing material supported by and engaged with such roofing supports.

7. The combination with a roof having inclined wooden rafters of a series of roofing supports extending across the rafters and each comprising a metal strip of channel formation having a central portion perforated at uniform intervals between two side flanges of which at least one side

flange has an edge adapted to obtain a grip on inclined wooden rafters and roofing material supported by such roofing supports and engaged therewith by nails passing through registering perforations of roofing material and of roofing supports, some of such nails entering the rafters and intermediate nails being bent under the roofing supports.

8. The combination with a roof having inclined wooden rafters of a series of roofing supports extending across the rafters and each comprising a longitudinally flanged metal strip of channel formation having a central portion between two side flanges of which at least one side flange is at an obtuse angle with the central portion of the strip and has a grip-obtaining edge in contact with the rafters at a lower level than any other point of contact of that strip with the rafters and roofing material supported by and engaged with such roofing supports.

9. The combination with a roof having inclined wooden rafters of a series of roofing supports extending across the rafters and each comprising a longitudinally flanged metal strip of channel formation having a central portion between two side flanges of which at least one side flange is at an obtuse angle with the central portion of the strip and has a crimped edge in contact with the rafters at a lower level than any other point of contact of that strip with the rafters, fixing devices passing through perforations of the roofing supports into the rafters and roofing material supported by and engaged with such roofing supports.

10. The combination with a roof having inclined wooden rafters of a series of roofing supports extending across the rafters and each comprising a plurality of nested longitudinally flanged metal strips of channel formation, each strip having a central portion between two side flanges of which at least one side flange is at an obtuse angle with the central portion of the strip and the obtuse angled flange of the lowermost of the nested strips has a grip-obtaining edge in contact with the rafters at a lower level than any other point of contact of that strip with the rafters and roofing material supported by and engaged with such nested roofing supports.

11. The combination with a roof having inclined wooden rafters of a series of roofing supports extending across the rafters and each comprising a plurality of nested longitudinally flanged metal strips of channel formation, each strip having a central portion between two side flanges of which at least one side flange is at an obtuse angle with the central portion of the strip and the obtuse angled flange of the lowermost of the nested strips has a crimped edge in contact with the rafters at a lower level than any other point of contact of that strip with the rafters, fixing devices passing through perforations of the nested roofing supports into the rafters and roofing material supported by and engaged with such nested roofing supports.

JOHN BLANDY LLEWELLYN.
